HEAT REGULATOR FOR OVENS AND
THE LIKEWarren W. Sackett, Milwaukee, Wis., assignor to
Milwaukee Gas Specialty Company, Milwaukee,
Wis., a corporation of Wisconsin

Application December 14, 1931, Serial No. 580,819

18 Claims. (Cl. 236--15)

My invention relates to heat regulators for gas ovens and the like, and contemplates an improvement which will enable the thermal sensitive device of the regulator to pass, for example, through the side wall of the oven and into position indicative of the prevailing temperature within the oven, and in which the selecting device is operable from the front of the control panel of the range without positioning the entire 5 selecting dial mechanism externally of that panel and without disposing the axis of the dial at right angles to the axis of the selecting spindle which passes through the oven wall and cooperates with the thermal sensitive device.

10 In the use of gas ranges, the side wall of the oven is sometimes so disposed that the selecting dial either cannot be disposed on the outer end of the spindle which cooperates with the thermal sensitive device, or is not conveniently accessible when so disposed. It also frequently is not desirable to dispose the axis of the selecting device at right angles to the axis of the spindle which cooperates with the thermal sensitive device, and where the oven is of the cabinet type or has a 15 front control panel, frequently it is not desirable 20 to have the entire selecting dial mechanism outside of that panel.

My present invention provides a regulating device in which the axis of the dial may be positioned generally parallel to the axis of the spindle 30 which cooperates with the thermal sensitive device and in offset relation with respect thereto. This enables passing the thermal sensitive device of the regulator through the wall of the oven and into position indicative of the prevailing temperature within the oven and at the same time 35 enables disposition of the selecting dial in proximity to the front of the range for access thereto.

40 My invention further provides a device in which the selecting dial and other parts may be substantially completely concealed, and in the illustrated embodiment the dial is of the drum type provided on its periphery with the finger piece 45 for manipulating the same, only a portion of which finger piece need be exposed through an opening in the control panel, the major portion of the dial and the other parts being adapted to be concealed behind that panel to present a 50 pleasing and finished appearance.

Another feature of my present invention resides 55 in the adaptability of the selecting device for positioning in different positions with respect to the thermal sensitive device, and particularly for disposition at the front of the range with the ther-

mal sensitive device applied to a left hand, right hand or other oven arrangement.

My invention still further provides a device of this sort comprising a selecting device, thermal sensitive device and control device which may be 5 assembled in precorrelated relation and installed as a unitary assembly.

I have referred to passing the thermal sensitive device of the regulator through the side wall of the oven and to positioning of the selecting dial 10 adjacent the control panel at the front of the range, and I shall describe hereinafter in connection with the drawings a device so installed, but it is to be understood that the device is not limited to this particular use or this particular 15 manner of installation but may be applied as suitable or desired.

In order to acquaint those skilled in the art with the manner of constructing and operating a device in accordance with my present invention, 20 I shall now describe in connection with the accompanying drawings certain embodiments of the invention.

In the drawings:

Figure 1 is a perspective view of a cabinet type 25 gas range, showing an embodiment of the present invention in connection therewith;

Figure 2 is a horizontal section taken through the axis of the selecting dial and through the axis of the spindle which cooperates with the 30 thermal sensitive device substantially on the line 2—2 of Figure 1;

Figure 3 is a vertical section taken substantially on the line 3—3 of Figure 2;

Figure 4 is a view partially in section and partially in elevation and taken substantially on the line 4—4 of Figure 2; and

Figure 5 is a sectional view similar to Figure 2, showing a modification of the present invention.

Referring to the drawings, the reference number 40 10 indicates in its entirety a gas range of the cabinet type having an oven 11. The oven 11 has a door 11a provided with a suitable handle 11b. The range 10 has a front control panel 10a and valves 12 are positioned along this panel for 45 the purpose of controlling the flow of fuel to the top burners 13a, as well understood in the art. A hinged cover 13 provides a cover for the top burners, and this cover is adapted to be swung upwardly and backwardly about the hinge 50 means 13b along the rear edge of the cover. A valve 14 also on the control panel 10a controls the flow of fuel to the oven burner which is not shown but is situated beneath the oven 11.

Positioned in the embodiment shown in prox- 55

imity to the right hand end of the panel 10a is the selecting dial 15 provided with temperature markings 15a which are selectively positioned by turning of the dial in register with the marking 15b on the panel 10a for the purpose of setting the regulator to maintain any desired temperature within the oven. The panel 10a has a small slot 15c adjacent the dial 15, and the circular wall of the dial is positioned so that a small portion thereof is disposed in the slot 15c flush with the outer surface of the panel 10a. The dial 15 has a dial ring 17, a small portion of the knurled or roughened periphery of which extends slightly through the slot 15c so that the finger may be frictionally engaged therewith for the purpose of turning the dial to select the desired temperature to be maintained within the oven. As shown in Figure 4, one end of the slotted opening 15c is enlarged to accommodate the great diameter of the dial ring 17 with the relatively small portion of the dial 15 exposed at the opening 15c.

The radial wall of the dial 15 is provided centrally with an opening, and the dial ring 17 is provided with a similar registering opening for receiving the adjacent end of the control stem 20 and the dial and dial ring are secured in place upon this stem to turn the same therewith by means of friction washers 21, an abutting flange 22 and an adjusting screw 23 which has threaded engagement with the stem 20 and clamps the ring 17 and radial wall of dial 15 to the shoulder 22 with one friction washer between the head of the screw and the shoulder 22 and the other between the shoulder 22 and the adjacent radial wall of the dial. In case of any discrepancy between the setting of the dial and the action of the device, the screw 23 may be loosened slightly, the dial turned with respect to the stem 20 to the desired setting, and the screw 23 tightened to bind the dial firmly in set position.

The stem 20 is threaded into the dial bracket 32, which is of angular configuration, and has a projecting lug 25 in which is secured a stop pin 26. A radially disposed pin 27 secured to the inner surface of the circular wall of the dial 15 is adapted to contact with the pin 26 to limit the rotation of the dial member and associated control stem. With this arrangement it is possible to rotate the dial member 15 through almost a complete rotation, but it is not possible to unthread the control stem 20 from the bracket 24.

The stem 29 has a reduced portion 28 which engages in a slot 31 in a lever 29 which is fulcrumed at 35 upon a pin secured at its opposite end in lugs 34 integral with the bracket 32 and spaced to receive the lever 29 therebetween. The free end of the reduced portion 28 of the stem 20 has a head 30 which prevents displacement of the adjacent slotted end of the lever 29. The bracket 32 has an opening 33 providing access to the headed end 30 of the reduced stem portion 28, which reduced stem portion may be, if desired, formed separately from the stem 20 and threaded into the adjacent end thereof. By proper determination of the pitch of the threads securing stem 20 in bracket 32, it is possible to determine the effective longitudinal movement of the stem upon rotation of the dial 15, and this, in turn, makes it possible to determine the amount of movement imparted to lever 29 by turning of the dial.

The opposite end of the lever 29 is provided with an aperture into or through which extends the reduced outer end 36 of the spindle or ad-

justing pin 37. The pin 37 is mounted for axial sliding movement in a boss 38 integral with the bracket 32, and this boss is recessed at 39 to receive a spring 40 which engages with a washer as shown in Figure 2 and normally urges the shoulder adjacent the reduced end 36 of the stem 37 against the adjacent end of the lever 29.

The oven wall is indicated at 41 and has an inner lining or insulating wall 42 spaced inwardly therefrom. This provides an insulating air chamber 43 which is adapted to prevent too rapid transmission of heat from the oven to the exterior wall, and the inner wall is formed with a relatively oblong and vertically extending recess 43a opening inwardly at 43b into the interior of the oven and adapted to receive the thermal sensitive device of the regulator. This recess may be formed by bending the inner wall outwardly around the desired recess with the outer margins of the bent out portions of the lining contacting with the outer wall 41 as shown.

The outer wall 41 has an opening 44 through which the integral sleeve 45 at the upper end of the housing 46 for the thermal sensitive device is passed. The housing 46 at the outer end of the integral sleeve portion 45 provides shouldered abutment with the outer surface of the outer wall 41, and the housing 46 may be secured to the outer oven wall 41 by means of stud screws or bolts 47 inserted from within the recess 43a and passing through openings in the wall 41 and threaded into the housing 46.

The housing 46 has integral web-like flanges terminating in ears 49 and a rocker or fulcrum pin 50 extends between these ears and is secured at its opposite ends therein. The hollow boss 38 of the housing 32 is inserted in the integral sleeve 45 of the housing 46, the housing 32 at the outer end of the boss 38 having shouldered abutment with the housing portion at the outer end of the sleeve 45 and is secured in abutting contact therewith by means of a nut 51 threaded upon the inner end of the boss 38. In this manner the housing 32 with the selecting mechanism carried thereby is secured to the housing 46 carrying the thermal sensitive device so that these devices with their respective housings are joined together into a unitary assembly.

The inner end of the pin 37 has a reduced projection 52 which extends into an aperture in the upper end of the bi-metallic element 53. This element 53 is composed of strips of different metals and having different coefficients of expansion as well understood in the art, with the strip having the greater coefficient of expansion positioned on the left hand side of the element as viewed in Figure 3.

The bi-metallic element 53 has free abutting contact with the shoulder provided at the outer end of the pin 37 by the reduced portion 52 thereof, and the same side of the bi-metallic element has free abutting contact at its opposite end with a valve stem 54. Between its ends and upon its opposite side the bi-metallic element 53 has free abutting contact with the rocker or fulcrum pin 50, which, with the other free abutting contacts, effectively constrains the bi-metallic element and at the same time permits free warping action thereof. The outer end of the valve stem 54 cooperates with a valve member 55 of the "mushroom" type.

The housing or bracket 46 has an enlarged valve body 56 at its lower end. This valve body 56 is provided with an inlet chamber 57 and an outlet chamber 58. A bushing member 59 threaded into

the housing or bracket 46 provides a guide for the valve stem 54 and permits sliding movement of the valve stem therein. This bushing is threaded into an opening 60 in the valve body portion 56 5 and forms a gas-tight closure therewith. The valve member 55 has an outwardly extending central enlargement 61 around which the inner end of a generally conical spring 62 fits. The opposite and larger end of the spring 62 seats 10 in a recess 63 in a removable plug member 64 which is threaded into the valve body portion 56.

The valve body 56 has an integral flange forming a separating partition between the inlet and outlet chambers, which flange has the valve opening or port 65a and is recessed at 66 to provide a seat for the valve 55. A gas or other fuel inlet pipe 67 opens into the inlet chamber 57 and is connected to the valve housing 56 as by threaded engagement therewith. This pipe leads from 20 the gas manifold and the gas flow therethrough may be controlled by the control valve 14 shown in Figure 1, although it is to be understood that this pipe may be connected with any other source of fuel supply. A second pipe 68 opens from the 25 outlet chamber 58 and has connection with the oven burner. When the control valve 14 is open gas flows through the pipe 67 into the inlet chamber 57, and assuming the valve 55 is open, past this valve into the outlet chamber 58 from which 30 it flows through the pipe 68 to the gas burner or burners for the oven 11. It is understood that the form of the valve 55 and the other details may vary within the scope of the present invention.

35 A by-pass port 69 is provided through the wall 65 between the inlet and outlet chambers 57 and 58, and this port is flared at its outlet end for cooperation with the tapered end of an adjusting screw 70 threaded in the valve body 56 and provided for the purpose of adjusting the effective area of the by-pass 69. Threading the adjusting screw 70 into the valve body decreases the area of the by-pass 69 and this screw provides an adjustment for limiting the effective area of this 45 by-pass.

The by-pass 69 is provided for the purpose of permitting a predetermined minimum quantity of gas to flow through the control mechanism when the control valve 14 is opened. This small 50 quantity of gas ignites the burner and assures ignition whenever the valve 14 is opened. The small flame provided at the burner thereby might be termed a burner maintenance flame, and it assures ignition of the oven burner without the 55 operation of the control mechanism.

From the foregoing it will be apparent that all of the parts of the regulator may be assembled in pre-correlated relation and installed as a unit assembly and that the thermally responsive device is disposed so that its action will be indicative of the prevailing temperature in the oven. At the same time the controlling device comprising the valve mechanism in the valve housing 56 is disposed in proximity to the fuel feed 60 means for convenient connection therethrough and the selecting mechanism is disposed for convenient access from the front of the range. The relationship between the thermally responsive device and the controlling device may be 65 fixed in the unit assembly, and this relationship may be made and the device accurately gauged at the factory. The matter of installation therefore becomes a mere matter of appropriately applying the unit assembly and securing the same 70 in place by the screws 47.

In operation the dial is turned to bring the appropriate temperature marking into register with the marking 15b (Figure 1) by frictionally engaging the finger with the dial ring 17 and turning the same so that when the valve 14 is 5 opened the device maintains in the oven the temperature at which the dial is set. If the temperature exceeds that for which the device is set, the bi-metallic element 53 warps and permits the valve 55 to move towards its closed position 10 to reduce the supply of gas to the oven burner or burners, and if the temperature in the oven falls below that for which the device is set, the bi-metallic strip straightens and increases the opening of the valve 55 to increase the fuel supply to the oven burner. In turning the dial to set the device the turning of stem 20 produces a longitudinal movement thereof and this rocks the lever 29 about the fulcrum 35 to move the pin 37 inwardly or outwardly, depending upon the 15 direction of rotation. This movement of the pin 37 swings the bi-metallic strip 53 about its fulcrum to open the valve 55 therethrough or permits this bi-metallic strip 53 to be rocked about its fulcrum under the action of the spring 62 20 25 which thereupon moves the valve 55 toward its seat.

The embodiment of Figure 5 is formed to permit positioning of the selecting dial closer to the oven wall 41'. This lends itself to installations where the space is limited. In this embodiment the outer side wall of the oven is indicated at 41' and has the opening 75 for insertion of the thermal sensitive device within the oven proper or within the recess in the double walled construction as disclosed in the preceding embodiment. An outer facing wall or control panel corresponding to the panel 10a of Figures 1 to 4 is indicated at 76 and has an opening 77 in which the dial 78 is tangentially positioned for 30 visibility of a portion thereof through the opening. The dial 78 has the dial ring or hand wheel 79 corresponding to the dial ring 17 of the previous embodiment, and this dial ring may be of 35 bakelite or other suitable material and is knurled or roughened peripherally to provide a suitable finger grip.

The stem 80 is threaded into the L-shaped bracket which has the stem supporting portion 81. The stem 80 has an enlarged annular flange 82 50 against which a friction washer 83 has abutting engagement, and between this friction washer 83 and the end of the control stem I position the radial wall of the dial 78, the hand wheel or dial ring 79 and a second friction washer 84, and a 55 screw 85 is threaded into the stem 80 and clamps the dial and dial ring rigidly to the shoulder 82, it being understood that the dial may be turned with respect to the stem 80 to adjust for discrepancies by loosening the screw, turning the 60 dial with respect to the stem and then tightening the screw to bind the dial firmly and rigidly in set position.

The housing or bracket 86 is preferably cast of aluminum, brass or some suitable alloy. The 65 portion 81 of this bracket is threaded for threaded engagement with the threaded stem 80, and the bracket has a cut-away portion 87 permitting access to the reduced portion 88 of the stem 80. This reduced portion 88 of the stem 80 engages 70 in the slot 89 in the adjacent end of the pivoted lever 90. The housing 86 has projecting lugs 91 and a fulcrum or rocker pin 92 for the lever 90 extends between these lugs and is secured at its opposite ends therein. Rotation of dial wheel 75

78 rotates stem 80 which causes longitudinal movement of the slotted end 89 of the lever 90, and this forces the opposite end 93 of the lever 90 to move in the reverse direction. Rotation of stem 80 is limited by means of a stop pin 95 secured in the projecting flange 94 of the housing 86 and having stopping cooperation with a pin 96 projecting radially from the inner periphery of the dial 78.

10 The integral leg 97 of the housing 86 projects through the opening 75 in the oven wall 41, and this leg 97 is tubular and has mounted reciprocably therein a pin or plunger member 99. The inner end of the leg 97 is threaded to receive a nut 98 which secures the tubular leg 97 in the sleeve portion 102 of the control housing similar to the previous embodiment. The housing 86 has the recessed portion 103 which is adapted to receive the upper end 93 of the lever 90. The 15 plunger 99 is supported in the tubular leg 97 by means of a guide member 104 positioned in the end thereof. The other end of the plunger member 99 has a reduced portion 105 engaging in a slot in the upper end of the lever 90 as shown. 20 The outer end 106 of the plunger 97 is slidably supported in the housing 86.

25 The reduced inner end 107 of the plunger member 99 engages in an aperture in the bi-metallic strip 108 corresponding with the bi-metallic strip 30 of the previous embodiment. Ears 109 formed integral with the bracket part 102 support the opposite ends of a fulcrum or rocker pin 110 for the bi-metallic element 108 as in the previous embodiment, and the opposite end of this bi-metallic element has cooperation with the 35 control mechanism.

40 A virtue of the device of the present invention resides in the universal character of its construction. As shown, for example, in Figure 2 a lock pin 125 inserted into registering apertures in the bracket 32 and bracket 46 locks the bracket member 46 against turning movement on the boss 38 of the bracket member 32. In Figure 1 the oven 11 is shown at the right hand side of the top burners and the bracket members 32 and 46 are locked together for use with such an oven arrangement. Where the oven is at the 45 left hand side of the top burners, the lock pin 125 may be withdrawn, the bracket 32 rotated through 180 degrees with respect to the bracket 46 and the lock pin 125 inserted through an 50 aperture 126 in the bracket 32 and into the aperture in the bracket 46 in cooperation with which it is shown in Figure 2. This enables applying the 55 thermal sensitive device to an oven wall at the left hand side of the top burners and positions the selecting mechanism forwardly adjacent the control panel. The dial 15 may be replaced with another dial suitable for use in this position, or the temperature markings 15a on the dial 15 may 60 be so arranged that they will be suitable in either position of the dial. Obviously, the adjustable character of the device is not limited to swinging movement of the bracket 32 thru 180 degrees 65 with respect to the bracket 46, but other amounts of angular movement and a plurality of different angular positions of these members are contemplated within the scope of the present invention.

70 I do not intend to be limited to the precise details shown or described.

75 I claim:

1. The combination with a gas range having a front control panel and an oven provided with a side wall, of a heat regulator comprising a thermal sensitive mechanism extending through

the side wall of the oven, and a selecting device connected with said thermal sensitive mechanism and including a selecting dial disposed with its axis of rotation generally parallel to said front panel, said thermal sensitive mechanism being 5 disposed in a plane generally normal to the axis of rotation of said selecting dial.

2. The combination with a gas range having a front control panel and an oven provided with a side wall and an inner lining wall, said panel 10 having an opening, of a heat regulator comprising a thermal sensitive mechanism extending through the side wall of the oven and disposed between said wall and said lining wall, and a selecting device connected with said thermal 15 sensitive mechanism and including a selecting dial disposed with its greater portion concealed behind said panel, said dial having a dial ring accessible through the opening in said panel.

3. In combination, a planar thermal sensitive 20 device pivoted intermediate its ends, a plunger cooperable therewith and extending normal thereto, a selecting stem disposed with its axis generally parallel the axis of said plunger and offset with respect thereto, and a lever fulcrumed 25 between said plunger and said stem and cooperating with the plunger on one side of said fulcrum and with the stem on the opposite side of said fulcrum.

4. In combination, a thermal sensitive device 30 pivoted intermediate its ends, a plunger cooperable with one end thereof, a selecting stem disposed with its axis generally parallel the axis of said plunger and offset with respect thereto, a lever fulcrumed between said plunger and said 35 stem and cooperating with the plunger on one side of said fulcrum and with the stem on the opposite side of said fulcrum, a dial for said stem, a peripheral finger piece for said dial, and a control device connected with the opposite 40 end of said thermal sensitive device.

5. In combination, a bracket, a selecting device thereon, a housing swingably attached to said bracket, means for locking said housing against swinging movement with respect to said bracket, 45 a control device on said housing, a thermal sensitive device forming a regulating connection between said selecting device and said control device, said connection including a plunger cooperable with the thermal sensitive device, and the 50 selecting device having a dial disposed with its axis generally parallel to said plunger and offset with respect thereto.

6. In an oven, a control device comprising a control dial, a control stem cooperating with said 55 dial, a pivoted lever associated with one end of said control stem and extending at right angles thereto, a plunger engaging the other end of said lever, a valve and cooperating valve stem, actuating means for said valve stem adapted to cooperate with said plunger including a second pivoted lever whereby rotation of said control dial actuates said valve.

7. In an oven, a control device comprising a control dial, a control stem cooperating with said 65 dial, a pivoted lever associated with one end of said control stem and extending at right angles thereto, a plunger engaging the other end of said lever, a valve, a valve stem, actuating means comprising a pivoted thermally sensitive element for 70 said valve stem adapted to cooperate with said plunger whereby rotation of said control dial actuates said valve.

8. In combination, an oven having a side wall, a lining wall spaced inwardly from said side 75

- wall and having a recess therein, regulating mechanism for said oven comprising a rotatable selecting device disposed exterior to said side wall, a control device beneath said selecting device, and a thermally sensitive member disposed in said recess and transmitting movement of said selecting device to said control device, a panel for said oven extending normally with respect to said side wall and having a cut-out portion, and dial means extending partially through said cut-out portion and rotatable in a plane normal to said panel for operating said selecting device.
9. In combination, a heat regulator comprising a control device having a valve stem therein, thermally sensitive means having abutting engagement at one end with said valve stem, a selecting device having its axis of rotation normal to the plane of said thermally sensitive means, and motion transmitting means extending between said selecting device and the opposite end of said thermally sensitive means including a lever pivoted intermediate its ends and lying in a plane parallel to said thermally sensitive means, said selecting device being rotatable as a unit about said opposite end of said thermally sensitive means.
10. In combination, a selecting device having a threaded selecting spindle, a slideable plunger laterally offset from and extending parallel thereto, a housing having extending offset boss portions receiving said spindle and said plunger, respectively, a planar lever member pivoted intermediate its ends and disposed between the ends of said spindle and plunger, said lever extending normal to the axes of said spindle and plunger, and pivotally mounted thermally sensitive means engaging the free end of said plunger.
11. In a device of the class described, a housing having an offset collar portion, a second housing having a projecting boss portion secured in said collar portion, a valve and valve stem in said first housing, a pivotally mounted thermally sensitive member having one end engaged by said valve stem, a plunger slideable in said boss portion and engaging the opposite end of said thermally sensitive member, a selecting device carried by said second housing and including a spindle extending parallel to said plunger, motion transmitting means between said spindle and said plunger for transmitting axial movement of said spindle in one direction into axial movement of said plunger in the reverse direction, and pin means for fixing the radial position of said second housing with respect to said first housing.
12. In a cabinet type of gas range having an oven, a plurality of open top burners at one side of and adjacent the top of said range, and a hinged cover for said burners adapted, when closed, to lie in the plane of the top of said oven, the combination of a control panel for said open top burners mounted at the front of said range adjacent the top thereof and having a cut-out portion, control valves for each of said burners and for said oven carried by said panel, a heat regulator mechanism mounted on the side wall of said oven beneath said hinged cover and behind said panel, and means for operating said regulator mechanism having a portion thereof extending through said cut-out portion of said panel.

13. In combination, a housing, selecting means including a selecting spindle supported thereby, a planar lever pivoted intermediate its ends on said housing and engaged at one end by said spindle, a plunger carried by said housing and engaged at one end by the opposite end of said lever, said plunger being laterally offset from and extending parallel to said spindle, a second housing having control means therein, a thermally sensitive member pivoted intermediate its ends on said second housing and having one end engaged by said control means, said plunger having engagement at its other end with the opposite end of said member, and spring means for preventing any lost motion connection between said selecting means and said control means.

14. In combination, a thermal sensitive member, means having selecting cooperation with one end of said member and having abutting engagement therewith, selecting dial means disposed with its axis generally parallel to the axis of said last-named means and offset with respect thereto, means interconnecting said selecting means and said dial means for conjoint axial movement, and a control device suspended below said thermal sensitive member and having abutting engagement with the opposite end thereof.

15. In combination, a thermal sensitive member, an element extending normal thereto and having selecting cooperation therewith, a selecting device disposed with its axis generally parallel to the axis of said element and offset with respect thereto, linkage means for transmitting axial movement of said selecting device to said element, and means including a housing supporting said selecting device and having a rotatable bearing portion surrounding said element for adjusting the position of the selecting device about the axis of the element.

16. In combination, control means, selecting means, a pair of levers pivoted intermediate their ends and engaging said control means and said selecting means at the opposite ends thereof, and a plunger between said levers engaged by the adjacent ends thereof, said plunger being offset from and extending parallel to the axis of said selecting means.

17. In combination, a plunger adapted for reciprocatory movement, a pair of levers at opposite ends of said plunger and extending normally thereto, selecting means engaging the opposite end of one of said levers, control means engaged by the opposite end of the other of said levers, and means for varying the angular relation between said levers about the axis of said plunger.

18. The combination with a gas range having a front control panel and an oven provided with a side wall, said panel having an opening therethrough, of a heat regulator comprising a planar thermally sensitive element disposed in a recess in the side wall of the oven, and a selecting device connected with said thermally sensitive element and including a selecting dial disposed in a plane parallel to the plane of said thermally sensitive element with its greater portion concealed behind said panel and with a portion of the outer surface of said dial visible through the opening in said panel, said dial being adapted for manipulation from the front of the panel.
